(57) **CLAIM**

The ornamental design for a combined ice scraper and brush, as shown and described.

DESCRIPTION

FIG. 1 is a top perspective view of the combined ice scraper and brush, showing my new design;

FIG. 2 is a top plan view thereof;

FIG. 3 is a bottom plan view thereof;

FIG. 4 is a side elevation view thereof;

FIG. 5 is a top perspective view thereof, with the brush in an alternate position and the ice scraper in a retracted position;

FIG. 6 is a top plan view thereof, showing the ice scraper yet further retracted;

FIG. 7 is a bottom plan view the article as shown in FIG. 6; and,

FIG. 8 is a side elevation view the article as shown in FIG. 6.
